UNITED STATES PATENT OFFICE

157,798

INSECTICIDE VAPORIZER OR THE LIKE

Alfred D. Slatkin, Birmingham, Mich., assignor to Moth-King Corporation, Detroit, Mich., a corporation of Michigan

Application December 4, 1948, Serial No. 149,977

Term of patent 14 years

(Cl. D31—3)

To all whom it may concern:

Be it known that I, Alfred D. Slatkin, a citizen of the Dominion of Canada, residing in Birmingham, in the county of Oakland and State of Michigan, have invented a new, original, and ornamental Design for an Insecticide Vaporizer or the like, of which the following is a specification, reference being had to the accompanying drawing, forming part thereof.

Fig. 1 is a perspective view of an insecticide vaporizer or the like embodying my new design.

Fig. 2 is a side elevational view thereof, and

Fig. 3 is a top plan view thereof.

I claim:

The ornamental design for an insecticide vaporizer or the like, as shown.

ALFRED D. SLATKIN.
